[57] CLAIM

The ornamental design for a combined wireless telephone and keyboard, as shown and described.

DESCRIPTION

FIG. 1 is a perspective view of a first embodiment of a combined wireless telephone and keyboard showing our new design;

FIG. 2 is a top plan view thereof;

FIG. 3 is a left side elevational view thereof, a right side elevational view thereof being a mirror image;

FIG. 4 is a front elevational view thereof;

FIG. 5 is a bottom plan view thereof;

FIG. 6 is a rear elevational view thereof;

FIG. 7 is another perspective view thereof wherein the cover is in the closed position;

FIG. 8 is a rear elevational view of a second embodiment of a combined wireless telephone and keyboard showing our new design; and,

FIG. 9 is a perspective view thereof wherein the cover is in the closed position, the rest of the views of the second embodiment being the same as those of the first embodiment.
